APPARATUS FOR LOADING RAILS AND TIES

Ernest R. Breaker, San Antonio, Tex.

Application April 30, 1934, Serial No. 723,113

1 Claim. (Cl. 104—2)

This invention relates to new and useful improvements in apparatus for loading rails and ties.

Temporary railroad tracks are laid for various purposes and it has been found that after serving their purpose, the rails and ties are still in good condition and it has been found profitable to salvage these rails and ties which comprise the temporary track. However, the expense and labor involved has almost made it prohibitory to salvage the rails and ties, because of the difficulty experienced in loading said rails and ties onto cars for hauling.

One object of the invention is to provide improved apparatus for quickly, expeditiously, and inexpensively loading rails and ties onto railway cars.

Another object of the invention is to provide improved apparatus for loading railroad ties onto railway cars which includes a conveyor extending from the roadbed where the ties to be loaded are positioned, to a desired railway car which may be connected at any point in the string of cars comprising the train.

An important object of the invention is to provide improved apparatus for loading rails onto railway cars which includes a guide mounted on the end of the car closest to the rails to be loaded, and means arranged to be attached to the rail to be loaded for pulling said rail through the guide onto the cars.

A further object of the invention is to provide improved apparatus for loading railway ties which includes an overhanging or cantilever type conveyor which is mounted above the cars of the train, whereby the ties may be carried over any number of cars and deposited on any desired car in the train.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is an elevation of a train of cars having rail and tie loading apparatus, constructed in accordance with the invention, mounted thereon.

Figure 2 is an enlarged partial elevation of the rear car.

Figure 3 is a plan view of the same.

Figure 4 is an enlarged end elevation of the tie conveyor.

Figure 5 is a vertical sectional view, taken on line 5—5 of Figure 4, and,

Figure 6 is a detail of the conveyor gearing.

In the drawings the numeral 10 designates a train including the locomotive 11, flat cars 12, and gondola car 13. The train may include any desired number of cars and of any type, but for purpose of illustration I have shown two flat cars and one gondola car, but it is to be understood the invention is not limited to the number of cars in the train.

When a railroad track is being dismantled, the rails are taken up in sections, and it is the purpose of the invention to run the train immediately ahead of that section of the track which is being dismantled. The entire loading mechanism for loading the rails onto the flat cars is mounted on a rear car 15. This car has a rail guide 16 secured to its extreme rear end at one side thereof. The guide is formed of a section of channel iron which is bent upon itself at right angles so as to form a depending leg 17. It is pointed out that the bend in the channel bar is curved thereby eliminating a sharp corner.

A cable 18 is positioned to travel within the guide 16, and travels forwardly of the train, and passes over a pulley 19, which is preferably mounted at the forward end of the flat car on which the rails are to be loaded. After it passes over this pulley the cable extends rearwardly and is secured to a winch head or drum 20 which is driven by a suitable motor or other power unit 21. The cable 18 is provided with a hook 18' at its end and this hook is engaged in one of the bolt holes 14' of the loosened section of the rail 14. By starting the motor 21 it is obvious that the cable will be wound around the drum 20 and will pull the section of rail 14 upwardly through the guide 16 on to the rear flat car 15. Further, rotation of the drum 20 will pull said rail onto the next car.

The motor is then stopped and the cable disconnected from the rail. The cable is then unwound from the drum 20, and is connected to the next section of the rail which is to be drawn onto the cars. It is pointed out that the channel bar 16 provides a simple guiding means for the rails, as they are pulled onto the car 15, whereby rails are held in alignment with the cable and a direct pull by said cable is had. Further, the guide will take all the wear caused by the rails being pulled therethrough.

When the rails have been removed from the ties and loaded onto the cars, as hereinbefore described, it is then necessary to load said ties

onto a car which must necessarily be ahead of the cars on which the rails are loaded. For loading the ties on the proper cars I provide a conveyor 22. The conveyor is supported above the 5 cars by a suitable structure 23 which is secured to the sides of the cars. This structure may comprise a plurality of vertical standards 23' which have their lower ends supported in the usual stake pockets 24' which are provided on 10 the sides of each car. By mounting the standards in the usual stake pockets, it will be seen that the conveyor structure may be readily assembled or disassembled on any ordinary flat car. The conveyor comprises a pair of channel 15 bars 24 (Figure 4) which are positioned in the same horizontal plane to form a channel therebetween, said bars being supported by the structure 23. Rollers 25 are mounted between the bars 24 in bearings 26 which are secured to the 20 underside of said bars and an endless belt 27 passes over the rollers. The channel bars may be the entire length of two or three cars or they may be made in sections of one car length. However, if they are made of one continuous piece 25 the rollers 25 are positioned so that each belt 27 extends only the length of one car. The rear section of the conveyor 22 is inclined downwardly so that its lower end is adjacent the railroad track. To provide for all the belts being driven 30 in unison and from a center power unit the shafts of the rollers 25 carry gears 28 on their outer ends. The gears 28 are connected together by a pinion 29 (Figure 6), and it is obvious that motion is imparted from one gear to the other. 35 By employing the gears and pinion it is possible to obtain a drive connection between the inclined section of the conveyor and the horizontal section whereby the belts 27 in each are driven together. The provision of the gears and 40 pinions also permits the connection to be made between the rollers 25 of individual sections, when individual sections are erected over each car. When the structure is made in sections, the pinion 29 may be carried by either section (Figure 45 6).

In loading the ties, said ties are placed lengthwise on the belt 27 in the channel formed between the bars 24 of the rear section 22 of the conveyor. The belt is then put into motion by 50 any suitable drive mechanism 30 which may be connected to one of the gears 28, and the ties will travel up the inclined section of the conveyor, and then along the straight portion of said conveyor, and then carried to any desired car which 55 might be positioned in the train. It is pointed out that regardless of the number of cars in the train the structure 23 can be secured on all the cars, whereby the conveyor may be any desired length. It is of course necessary to remove the ties from the conveyor and stack the same in the car in which it is desired to load them.

By placing the ties on the conveyor in a lengthwise position, it is not only easier to unload the same but it aids in stacking the ties lengthwise

in the car, as is required by some railroads. A single power unit may be employed for operating the cable and the conveyor, and it is noted that this unit can be permanently mounted on a single car. This car can also carry the guide 16 5 and the inclined section of the conveyor 22 whereby this car may be used in every loading operation and it is only necessary to substitute empty cars for the loaded ones.

Although I have shown the conveyor in one 10 section, it is again pointed out that said conveyor may be made of sections the length of one car. By using the several belts 27, it is not only possible to make the turn between the inclined section and the horizontal portion of said conveyor but a more substantial conveyor is provided than if one continuous belt were employed.

It is clear that while the rails and ties of one section of the car are being loaded, the next section which is immediately under the rear car 20 can be dismantled, that is, the bolts may be removed, so that when the train is moved, the rails and ties are ready to be loaded, thereby saving time and speeding up the work.

The description which has been given recites 25 more or less detail of a particular embodiment of the invention, which is set forth as new and useful; however, I desire it understood that the invention is not limited to such exact details of construction, because it is manifest that changes 30 and modifications may be made, within the scope of the appended claim, without departing from the spirit of the invention.

What I claim and desire to secure by Letters Patent is:

A railway track loading apparatus including, 35 a railway flat car, an angular rail guide at one end of said car, a cable travelling within said guide for pulling rails onto the car through said guide, a superstructure built on said car, a pair 40 of horizontal channel bars supported on said superstructure, an elongate inclined member extending from the end of the channel bars downwardly to the railway track, a belt conveyor within the inclined member and the channel bars, 45 a common driving means for operating the conveyor and the cable, whereby rails and ties may be removed from the track simultaneously, a second railway flat car having stake pockets on its sides, a superstructure supported in said pockets, a pair of horizontal channel bars carried by the superstructure, said bars being in alignment with the channel bars of the first car to form a continuation thereof, a conveyor belt within the channel bars, a gear carried by the 50 end of the bars on the first car and rotated by the travel of the belt conveyor, a similar gear carried by the end of the channel bars above the second car for driving the conveyor belt 55 whereby the belts are operated simultaneously 60 to form a continuous conveyor.

ERNEST R. BREAKER.
